UNITED STATES PATENT OFFICE.

FERDINAND VON MADALER AND ARTHUR DE MADALER, OF HAMPTON BAYS, NEW YORK, ASSIGNEES TO VISION-TONE CORPORATION, OF NEW YORK, N. Y., A CORPORATION OF NEVADA.

DESIGN FOR A CASING FOR A COMBINATION HOME MOTION-PICTURE MACHINE AND PHONOGRAPH.

Application filed November 1, 1928. Serial No. 28,730. Term of patent 3½ years.

To all whom it may concern:

Be it known that we, FERDINAND VON MADALER and ARTHUR DE MADALER, citizens of the United States of America, and residents of Hampton Bays, in the county of Suffolk and State of New York, have invented a new, original, and ornamental Design for a Casing for a Combination Home Motion-Picture Machine and Phonograph, of which the following is a specification, reference being had to the accompanying drawing, forming part thereof.

The figure is a perspective view of a casing for a combination home motion picture machine and phonograph showing our new design.

We claim:

The ornamental design for a casing for a combination home motion picture machine and phonograph as shown.

FERDINAND VON MADALER.
ARTHUR DE MADALER.
